UNITED STATES PATENT OFFICE.

CLARKE P. POND, OF PHILADELPHIA, PENNSYLVANIA.

SASH CONSTRUCTION.

1,283,555.

Specification of Letters Patent.

Patented Nov. 5, 1918.

Application filed June 29, 1910. Serial No. 569,538.

To all whom it may concern:

Be it known that I, CLARKE P. POND, a citizen of the United States, residing in Philadelphia, Pennsylvania, have invented 5 certain Improvements in Sash Constructions, of which the following is a specification.

One object of my invention is to provide a novel construction of building having a 10 line of any number of windows adjacent each other, with a single elongated sash whereby all of said windows may be closed or opened; the sash being so constructed as to provide a continuous weather shed extending the entire length of the building or 15 for any desired portion thereof as may be required.

I further desire to provide a novel form of sash construction which shall permit of 20 the satisfactory ventilation of various forms of roofs such as those of the monitor and saw tooth type, regardless of the weather conditions and without permitting the entrance of rain, snow, or the like.

25 I also desire to provide an improved sash construction for roofs which shall permit of the use of a line of windows without requiring any mullion or other intermediate structures between said windows; the only 30 vertical structural work employed being the truss members for supporting that part of the roof above the windows.

Again, I desire to provide a roof or similar structure having a line of windows or a 35 single horizontally elongated window, with an adjustable sash of improved construction so mounted that it shall be weather tight at its top edge in all positions and so arranged as to likewise be substantially 40 weatherproof at its ends.

Another object of my invention is to provide a horizontally elongated and continuous sash structure particularly designed for use in connection with one or a series of 45 windows, in combination with mechanism whereby the entire sash as a whole may be swung to a uniform extent upon its supporting structure in order to open or close the window.

50 These objects and other advantageous ends I secure as hereinafter set forth, reference being had to the accompanying drawings, in which:—

Figure 1, is a perspective view illustrating 55 my invention as applied to a monitor roof;

Fig. 2, is a vertical section of a structure similar to that illustrated in Fig. 1;

Fig. 3, is a horizontal section on the line a—a, Fig. 2, and

Fig. 4, is a vertical section showing my 60 invention as applied to a roof of the "saw tooth" type.

In Figs. 1 and 3 of the above drawings, 1 represents the vertical structural members supporting or forming a part of a monitor 65 roof and these are connected to the top and diagonal truss members 2 and 3 in any desired manner, as by a plate 4. The roof proper is indicated at 5 and the base of the monitor portion is shown at 6, so that in the 70 present case the structural members 1 extend vertically between these two parts and form the only elements extending across the window opening, which according to my invention, may be as long as the length of the 75 monitor and as wide as the distance between the parts 5 and 6.

In order to support a sash for closing this window opening, I preferably mount a Z-bar 7 in the under side of the edge of the 80 roof 5 and to this hinge the upper edge of the sash 8, which is preferably provided with an angle or other structural member 9 for the attachment of the necessary hinges.

The lower edge of the sash is likewise provided with a structural member 10;—in this case a T-iron, and has any desired number of vertical and longitudinal bracing members as shown, which are also employed as a 85 means of support for the glass panes or 90 window lights 11. While it is of course possible that the entire length of the sash may be made as a single rigid structure, I find it preferable for commercial reasons to make it in a number of separate sections, each of 95 whose vertical edges are defined, in the case illustrated, by an angle iron 12, and in order that the joint between the edges of adjacent sections may be weather proof, I so mount a channel member 13 as to cover the projecting webs of both angles; rigidly fixing it to the angle of one section and leaving it independent of the angle of the other section.

The hinge or pivotal supporting means whereby the sash structure is supported from the Z-bar 7, is so arranged that the top edge of said sash structure is underneath the main portion of said Z-bar and above its lower edge, thus effectually preventing any leakage between these two members.

For the purpose of simultaneously swinging all of the parts of the sash structure on their supporting hinges to a uniform extent, I may use any suitable device capable of accomplishing this end, and I preferably employ that particular form of sash operating mechanism described and claimed in my Patent No. 886,851, granted May 5, 1908, as illustrated in the drawings. This consists of 5 two longitudinally movable rods 14 and 15 mounted to extend parallel to the length of the sash structure and having connected to them T-shaped levers, of which those indicated at 16 are connected to the bar 15 and those indicated at 17 are connected to the bar 14. Each of these levers is fulcrumed to one of the vertical roof members 1 and has one of the ends of its cross member connected to one of the rods 14 or 15 as the case may be, 10 while its other end is connected to one end of a strut 18 whose opposite end is in turn connected to the sash structure 8.

By means of the apparatus shown in my patent above referred to or by any other suitable device, the rods 14 or 15 may be moved in opposite directions when it is desired to open the window and all of the levers are thereby caused to push outwardly to an equal extent upon the struts 18. The 15 sash structure is thus swung outwardly on its hinges or pivots to any desired extent so that a very complete and rapid ventilation of the building is secured, while at the same time it is a practical impossibility for 20 rain or snow to enter, since the opening of said window is between the top of the wall structure 6 and the bottom edge of the sash structure.

If the roof be of the "saw tooth" type as 25 shown in Fig. 4, the arrangement of parts is substantially the same as heretofore described except that in the case illustrated I have shown the roof as equipped with a fixed elongated sash structure 8^a whose top edge terminates in an angle iron 20. The 30 movable sash structure 8 extends between the angle iron 20 and the lower of a pair of angle irons 7^a, which in this instance are so arranged as to take the place of the Z-bar 35 previously used; the top edge of the sash structure extending upwardly under the lower one of said irons.

In this case the structural members 1 and the roof proper 5 are inclined in the well 40 known manner, although otherwise the structure of my invention is substantially the same as above described.

In order to prevent entrance of rain, etc., at the ends of the sash when the latter is in 45 its open position, I provide a stationary sash section 8^b which in effect underlaps the said sash, preferably to the extent of the width of one window light.

For this purpose said stationary section 50 is mounted slightly within the plane of the

window opening at its end farthest from the sash and is connected to a second stationary sash section 8^c by means of a strip or sheet of metal 25 which is so joined both to the said stationary section 8^c as well as to the glass carried by itself as to effectually prevent leakage at these points. At its opposite end the section 8^b is provided with a double strip of sheet metal 26 extending vertically and forward toward the movable sash 8 so as to practically contact with this when it is in its closed position.

In order that a tight joint may be made between the stationary end member 6^a of the building and the sash section 8^c, I provide 70 a channel shaped edge piece for said section as indicated at 13^a and at the same time mount on said part 6^a a plate 19 in such position that it has a vertical projecting edge over which the member 13^a extends.

With this arrangement when said sash is 75 opened it is a practical impossibility for rain or snow to enter the building through the triangular aperture between the end of the sash and the stationary section 8^c because of the overlapping above described.

It will be understood that this construction is provided at both ends of the movable sash and may be used not only with that construction shown in Figs. 1 to 3 inclusive, 80 but also that shown in Fig. 4.

I claim:—

1. The combination in a building structure having a horizontally elongated window opening of one or more structural members extending across said opening and dividing it into a series of windows; a single elongated sash formed of a number of structurally independent sections movably supported on said building structure 100 in position to simultaneously open or close all of said windows; and means for connecting each pair of adjacent section edges, the same consisting of projecting flanges on said edges; with a channel section fixed to 105 one of said flanges and extending around though mechanically free from the other.

2. The combination of a building structure having a swinging window sash; with means for preventing entrance of rain, etc., at the sides thereof when said sash is in its open position, the same consisting of auxiliary stationary sashes extending substantially parallel with and to the rear of the swinging sash when this is closed and overlapped by the sides of the latter.

3. The combination of a building structure having a window opening; a sash hinged at its upper edge to the top of said opening so as to be capable of swinging; 115 with auxiliary stationary sashes at the sides of the movable sash extending inside of and underlapping said sides.

4. The combination of a building structure having a window opening; two par-

- allel stationary sash sections at each end of said opening; with a movable sash section mounted on the building structure in position to overlap one stationary sash section 5 of each pair and lying substantially parallel with the plane of the other section when in its closed position; with means for moving said movable sash section away from the stationary sections to an open position.
- 10 5. The combination with a building structure having a window opening, of a swinging sash structure for closing said opening; and means for preventing the entrance of rain, etc., at the sides of said sash when the latter is in its open position, the same consisting of an additional sash mounted at the end of said first sash in a plane substantially parallel with the same when it is in its closed position and underlapping the end 15 of the first sash.
- 15 6. The combination of a building structure having a horizontally elongated window opening; with a series of structurally independent sash sections mounted on the building structure and forming a single laterally elongated sash for said opening; means for connecting the adjacent edges of said sash sections to form weathertight joints consisting of an outwardly projecting 20 flange on one edge and a coöperating channel shaped section mounted on the adjacent edge in position to overlap said flange though mechanically free from the same; means for movably supporting the sash sec- 25
- tion; and means for simultaneously moving all of the sash sections to a uniform extent.
7. The combination in a building structure having a window opening, of a rolled structural section in the form of a Z bar at the top edge of said opening; said section 40 having one flange fixed to the building and the other extending downwardly; with a swinging sash hinged to said latter flange and having its top edge extending above and to the rear of the same. 45
8. The combination with a building structure having a horizontally elongated window opening, and a series of structurally independent sash sections all in the same plane and hinged to said structure adjacent the 50 top edge of said opening in positions to close the same; of means for forming weather-tight joints between each pair of adjacent sash edges consisting of a projecting member on the edge of one sash and an overlapping member mechanically free of said first member connected to the edge of the other sash; and means for simultaneously moving all the sash sections to a uniform extent. 55
- In testimony whereof I have signed my name to this specification in the presence of two subscribing witnesses.
